SOLDERING GUN HANDLE

Leonard P. Young, Chester, Conn.

Application February 2, 1955, Serial No. 34,342

Term of patent 14 years

(Cl. D26—1)

FIG. 2.

FIG. 1.

FIG. 3.

FIG. 4.

FIG. 5.

Fig. 1 is a side elevation of a soldering gun handle, showing my new design;

Fig. 2 is a left-hand end view thereof;

Fig. 3 is a right-hand end view thereof;

Fig. 4 is a top view thereof; and

Fig. 5 is a bottom view thereof.

I claim:

The ornamental design for a soldering gun handle, as shown.
